CLAIM

The ornamental design for control unit, as shown and described.

DESCRIPTION

FIG. 1 is a top front right isometric view of our new invention for a control unit.

FIG. 2 is a top rear left isometric view of FIG. 1.

FIG. 3 is a bottom front left isometric view of FIG. 1.

FIG. 4 is a bottom rear right isometric view of FIG. 1.

FIG. 5 is a front side elevation view of FIG. 1.

FIG. 6 is a back side elevation view of FIG. 1.

FIG. 7 is a left side elevation view of FIG. 1.

FIG. 8 is a right side elevation view of FIG. 1.

FIG. 9 is a top plan view of FIG. 1; and,

FIG. 10 is a bottom plan view of FIG. 1.

The right arm of the control unit contains an extended feature along with a display and display support shown in light grey and forms no part of the claimed design.

1 Claim, 10 Drawing Sheets
